CLAIM

I claim the ornamental design for a wall block, as shown and described.

DESCRIPTION

FIG. 1 is a perspective view of a wall block according to a first embodiment, as viewed from the front, top, and one side of the block.

FIG. 2 is a side elevation view of the block of FIG. 1, the opposite side being a mirror image thereof.

FIG. 3 is a front elevation view of the block of FIG. 1, the rear elevation view being a mirror image thereof.

FIG. 4 is a top plan view of the block of FIG. 1.

FIG. 5 is a bottom plan view of the block of FIG. 1.

FIG. 6 is a perspective view of a wall block according to a second embodiment, as viewed from the front, top, and one side of the block.

FIG. 7 is a side elevation view of the block of FIG. 6, the opposite side being a mirror image thereof.

FIG. 8 is a front elevation view of the block of FIG. 6, the rear elevation view being a mirror image thereof.

FIG. 9 is a top plan view of the block of FIG. 6; and,

FIG. 10 is a bottom plan view of the block of FIG. 6.

The dashed lines in the drawings represent unclaimed portions of the design.
